UNITED STATES PATENT OFFICE.

JOHN BYSTROM, OF CHICAGO, ILLINOIS.

EXTENSION-HANGER FOR LAMPS.

SPECIFICATION forming part of Letters Patent No. 753,850, dated March 8, 1904.

Application filed October 19, 1903. Serial No. 177,644. (No model.)

To all whom it may concern:

Be it known that I, JOHN BYSTROM, a citizen of the United States, residing at Chicago, in the county of Cook and State of Illinois, have 5 invented certain new and useful Improvements in Extension-Hangers for Lamps, of which the following is a specification.

This invention refers to that form of extension-hangers in which a (clock) spring is employed to sustain the weight of the lamp and its contents. While the tension of such spring remains constant, the weight of the lamp varies from time to time, and as a consequence when the lamp is newly filled the spring is not sufficiently strong to support it, and when the oil in the lamp is nearly exhausted the tension of the spring tends to raise the lamp from a lowered position. The necessity for a locking means to hold the lamp in any desired position is manifest, and it is desirable that this locking means act to prevent either an unintended upward or downward movement of the lamp.

One of the objects of this invention, therefore, is the production of an easily-operated positive-locking device for hangers of the character mentioned.

A further object of the invention is the production of an extension-hanger embodying the 30 improvements in detail hereinafter pointed out.

In the accompanying drawings, Figure 1 is a top plan view of a hanger embodying the features of my invention. Fig. 2 is a vertical 35 central section through said hanger, taken on dotted line 2 2 of Fig. 1. Fig. 3 is a fragmental view, partly in section, showing the locking device. Fig. 4 is a view of a modified form of lock.

40 In the construction of this hanger I provide a suspension-stem 1, having at its upper end an integral suspending-loop 2 for suspending the hanger from a hook or other suitable support. The stem 1 has a slot 3 extending longitudinally therethrough and at its lower end is reduced in diameter to form the shoulder 4. A horizontal base-bar 5 has a central opening 6 for receiving the lower end of the suspension-stem 1, and surrounding said opening is 45 an annular boss 7, upon which the shoulder 4

of the stem 1 is adapted to rest. The stem 1 is held rigid with the base-bar 5 by means of a nut 8, adapted to be placed upon the screw-threaded portion of said stem. At the outer ends of the base-bar 5 are integral brackets 55 9 and 10, in which brackets are journaled sheaves 11 and 12, respectively. Ears 13 and 14 are also formed integral with the opposite ends of the base-bar 5, said ears being perforated to provide means, as the rivets 15, for 60 the attachment of an ornamental shield or cover 16 to the under side of said base-bar. Adjacent to the bearing-bracket 10 the base-bar 5 is provided with an integral boss 17, in which is formed the radial channel 18, the floor 65 of said channel being inclined toward the center of the bracket. The top and rear sides of the channel 18 are closed by means of an angle-plate 19, secured to the outer end of said boss by means of screws 20. 70

A lamp-supporting yoke 21 is carried by means of the chains 22 and 23, the inner ends of which chains are wound upon a drum 24, rotatably mounted upon the stem 1. These chains are wound upon the drum 24 in opposite directions and extend to the yoke 21, passing over the sheaves 11 and 12 and through openings 25 in the shell or casing 16. Stop-balls 26 are provided in said chains near the point of their attachment to the yoke 21, said balls being to limit the upward movement of 75 said yoke. The drum 24 is formed of two disks 27 and 28, joined together by a peripheral band 29, which band is provided with ears 30, adapted to extend through suitable 80 openings in the disks 27 and 28 and to be turned downward upon the outer faces of said disks. The disk 28 is provided in its periphery with notches 31 of dovetail outline, and both the disks 27 and 28 are centrally perforated and turned inward in the annular bearing-rings 32, by means of which bearing-rings a great bearing-surface for said drum is provided. A clock-spring 33 is attached at 85 its inner end to the stem 1 by passing through slot 3 therein, the outer end of the spring being secured to the drum 24 by means of the rivet 34, which passes through the two disks 27 and 28 of the drum and about which the outer end of the spring is wrapped. 90

100

A locking-roller 35 is provided for the channel 18 in the boss 17, said roller being free to move forward and backward in said channel. When in its forward position, the periphery 5 of said roller extends within one of the dovetail notches 31 in the lower disk 28 of the drum 24 and while it there remains locks said drum from rotation in either direction. The floor of the channel 18, within which the 10 roller 35 is confined, slants, as hereinbefore stated, toward the center of the hanger, and by reason of this the roller is normally thrown into engagement with the notches 31. The roller 35 is provided with a rim 36 of dovetail cross-section and upon its periphery with an annular bearing-rib 37, upon which latter said roller runs. To withdraw the roller 35 from engagement with the notched periphery of the disk 28, the yoke 21 is moved in the direction of the arrow 38 in the ball 26. This 15 movement of the yoke rocks the base-bar 5, so that the floor of the channel 18 is inclined away from the center of the hanger. If the drum 24 is now moved slightly by raising or 20 lowering the lamp, the roller 35 will be freed from engagement with the dovetail openings 31 in the periphery of the disk 28 and permitted to roll back within its said channel 18. The lamp may now be raised or lowered at 25 will, and when brought to rest in a normal position the roller 35 returns to the forward part of the channel 18 to enter the dovetail openings 31, as before. From the construction hereinbefore described it is manifest that 30 the drum 24 is locked by the roller 35 from rotation in either direction. The stem 1 is made removable in order that the slot 3 may easily be milled therein.

In Fig. 4 I have illustrated a modified form 40 of gravity-lock consisting of a pawl 39, pivotally supported upon a boss 40, extending from the side of the bracket 10^a, which bracket is formed integral with and extends upwardly from the base-bar 5^a. The pawl 39 is suspended in such manner as to normally swing 45 into engagement with notches 31^a in the lower disk 28^a. It is withdrawn from said notches by moving the yoke 21, as hereinbefore described. The walls of the channel 18 and the 50 cover 19 therefor form a housing for the roller 35.

It is clear that various changes may be made in the embodiment herein described without departing from the spirit and scope of my 55 invention. Therefore I desire not to limit myself to the precise details set forth.

I claim as my invention—

1. In an extension-hanger for lamps, in combination, a drum rotatable in a horizontal plane, said drum having a peripheral notch in its lower side; a spring for said drum; a suspension-chain adapted to be wound upon said drum; and a locking-roller arranged to engage the notch in said drum for positively locking the drum from rotation in either direction. 65

2. In an extension-hanger for lamps, in combination, a drum rotatable in a horizontal plane, said drum having a dovetail peripheral notch in its lower side; a spring for said drum; a suspension-chain arranged to be wound upon 70 said drum; and a locking-roller having a dovetail periphery arranged to engage the dovetail locking-notch in said drum.

3. In an extension-hanger for lamps, in combination, a base-bar; a drum rotatably 75 mounted upon said base-bar, said drum being provided with a locking-notch in its lower side; a spring for said drum; a suspension-chain arranged to be wound upon said drum; a housing supported by said base-bar; and a 80 locking-roller loosely supported in said housing and arranged to engage the notch in said drum.

4. In an extension-hanger for lamps, in combination, a base-bar provided at its ends 85 with integral bearing-brackets; sheaves journaled in said brackets; a drum rotatably supported upon said base-bar, said drum being provided in its lower side with a locking-notch; suspension-chains attached to said drum and 90 extending over said sheaves; a spring for said drum; a housing supported by said base-bar; and a roller loosely supported in said housing and arranged to engage the notch in said drum. 95

5. In an extension-hanger for lamps, in combination, a base-bar provided at its ends with integral bearing-brackets; sheaves journaled in said brackets; a stem fixed to said base-bar and provided with a suspension-loop; 100 a drum rotatably mounted upon said stem, said drum being provided with a locking-notch; suspension-chains attached to said drum and extending over said sheaves; a spring for said drum; a housing supported by said base-bar; and a roller loosely supported in said 105 housing and arranged to engage the notch in said drum.
